UNITED STATES PATENT OFFICE.

JOSEPH D. WILSON, OF KANSAS CITY, MISSOURI, ASSIGNOR OF ONE-HALF
TO FRANK J. MITCHELL, OF SAME PLACE.

CAR-COUPING.

SPECIFICATION forming part of Letters Patent No. 258,185, dated May 16, 1882.

Application filed February 23, 1882. (No model.)

To all whom it may concern:

Be it known that I, JOSEPH DOAN WILSON, of Kansas City, in the county of Jackson and State of Missouri, have invented a new and useful Improvement in Car-Couplings, of which the following is a full, clear, and exact description.

The object of this invention is to provide self-acting car-couplings which are adapted to be attached to and used with the ordinary link-and-pin draw-heads in common use.

My invention consists principally of suitable collars adapted to be attached to the draw-heads by pins passing through the collars and down through the ordinary pin-holes in the draw-heads, or by other suitable means, the collars being provided with suitable locking devices, and adapted to be rocked or partially rotated upon the draw-heads, preferably by means of shifting or movable counterbalance-weights or pivoted weighted levers for coupling and uncoupling the cars.

My invention also consists of the special construction and operation of the locking devices and of the means for unlocking the same, and also of the construction, arrangement, and combination of parts, all as hereinafter fully described.

Reference is to be had to the accompanying drawings, forming part of this specification, in which similar letters of reference indicate corresponding parts in all the figures.

Figure 1 is a plan view of my new and improved car-couplings as they appear when in locked position. Fig. 2 is a side elevation of the same. Fig. 3 is a sectional elevation taken on the line *x x* of Fig. 1, the weighted lever being turned so as to hold the collar in position for coupling the cars; and Fig. 4 is a sectional elevation taken on the line *y y* of Fig. 1, the weighted lever being turned so as to hold the collar in position for uncoupling the cars.

AA represent the collars, which are attached to the ordinary draw-heads, BB, by the pins CC, which pass down through the holes *a a* and *b b* in the upper and lower parts of the collars and through the ordinary pin-holes in the draw-heads, as clearly shown in the drawings.

The collars are formed upon the inside with the projections *c c*, which rest upon the draw-

heads and support the collars, and the holes through the collars, through which the pins pass, are elongated laterally, or to the right and left from the pins, as shown clearly in Fig. 1, to permit the partial rotation or rocking movement of the collars upon or around the draw-heads for bringing the collars into position for coupling and uncoupling the cars. This partial rotation or rocking movement of the collars is produced by the weighted levers DD, which are pivoted upon the upper side of the collars to the lugs *d d*, formed thereon, as shown in the drawings.

The collars are formed with the catches FF, which are upon opposite sides of the collars 65 as the collars face each other, and the collars are provided upon the side opposite to that upon which the catches are formed with the pivoted and hooked levers or arms EE, which are held in horizontal position by the spring rods ee, and are adapted, when the weighted levers are properly placed for the purpose—that is, when they are so placed as to hold the collars square upon the draw-heads, as shown in Fig. 3—to automatically drop over 70 the catches FF when the cars are brought together, and thus couple the cars.

To the outside of the spring-actuated hooked arms EE are pivoted the levers GG, and in rear of the latches EE are pivoted, to the side 80 of the collars, the beveled blocks HH. The levers GG are attached to the weighted levers DD, between the pivots of the latter and their outer ends, by the rods ff, bell-crank levers II, and the rods gg, as clearly shown in the 85 drawings, and the blocks HH are attached to the weighted levers, below the pivots thereof, by the rods hh, bell-crank levers JJ, and the rods ii, also clearly shown in the drawings. The forward ends of the levers GG are adapted, when the cars are coupled, to rest upon the upper edges of the catches FF, as shown in Figs. 1 and 2, and when the weighted levers are thrown over to unlock the hooked arms EE for uncoupling the cars the rear ends of the levers GG will be raised through the medium of their connections with the weighted levers just described, which will throw the forward ends of the said levers downward against the catches FF, and thus serve to raise the hooked 95 100

arms and insure their disengagement from the said catches; and the pivoted blocks H H have an upward movement upon their pivots when the weighted arms are thrown over for uncoupling the cars, and come against the lower diagonal faces of the hooked arms and serve as additional means for insuring the disengagement of the hooked arms from the catches.

In the bottom and to one side of the collars are placed the set-screws k k, by which the level of the collars may be adjusted, so that their movement upon the draw-heads will not be too great when the weighted levers are shifted for bringing the collars into position for coupling, but will cause the collars to be held on a level, or nearly on a level, with the draw-heads, as shown in Fig. 3.

To bring the collars into locking position the weighted levers must be shifted to the side of the collars opposite to that upon which the set-screws k k are placed. When in this position both collars will be held square upon the draw-heads, so that when the cars approach each other the hooked arms will automatically ride over and engage with the catches F F, and thus connect the cars.

For uncoupling the cars it is only necessary to throw or shift the weighted levers to the opposite side of the collars, which may be done from the top or platform of the cars by means of the chains or other suitable connections, j j, reaching to the top or platforms of the cars, or from the ground between the cars, by throwing or tossing one lever over by hand and drawing the other over by pulling upon the chain or other connection, which shifting of the levers will partially rotate, rock, or tilt the collars upon the draw-heads in opposite directions and bring one of them to the position shown in Fig. 4, which will correspondingly elevate the hooked arms and depress the catches sufficiently to disengage the arms from the catches and disconnect the cars. The action of the levers G G and the pivoted blocks H H will insure and cause the simultaneous disengagement of the hooked arms from the catches, as above described.

In most instances the collars will be made of such size relative to the size of the draw-heads, and be adapted to such distance of rocking movement, that the throwing over of one of the weighted levers will rock or rotate the collar sufficiently to completely disconnect both hooked arms from the catches.

In front of the bell-crank levers I I are placed the blocks L L, which protect the bell-crank levers and the rods connected therewith from all danger of being bent, misplaced, or otherwise injured.

By this construction of the couplings it will be seen that they are adapted to be easily attached to and used with the ordinary draw-heads; that the coupling is entirely automatic and certain; that the uncoupling can be quickly and easily performed, and that the couplings do not interfere with the use of the link and

pin for coupling, in case one of the cars should not be provided with my improved coupling.

For cars of medium height the collars will have the catches and the hooked arms made upon and attached to them about midway of the sides of the collars. For cars lower than the medium height the arms and catches will be made and attached higher up upon the collars, and for cars higher than the medium the hooked arms and catches will be made lower down on the sides of the collar, so that cars of all heights may be coupled with my improved couplings.

It will be understood that the blocks H H and the levers G G are not indispensably essential to the successful operation of my improved couplings, and that they may be omitted, if desired.

It will be noticed that the springs e e, besides holding the hooked arms E E, of which they are a rearward extension, in position for engaging with the catches F, are also designed and calculated to support the collars and the hooked arms in proper position to meet each other evenly for coupling.

Having thus fully described my invention, what I claim as new, and desire to secure by Letters Patent, is—

1. In car-couplings, a collar provided with suitable locking devices, and adapted to have a partial rotation or rocking movement upon the draw-heads, for coupling and uncoupling the cars, substantially as described.

2. The collar A, provided with the hooked arm E upon one side and the catch F upon the other, in combination with the pivoted weighted lever D, for partially rotating or rocking the collar, substantially as described.

3. The collars A A, adapted to be attached to the ordinary draw-heads, and adapted to have partial rotation or a rocking movement upon the draw-heads, substantially as described.

4. The collar A, formed with the elongated holes a and b, and with the projection c, substantially as and for the purposes set forth.

5. The collar A, formed with the elongated openings a and b, and with the projection c, in combination with the shifting weighted lever D, as and for the purposes set forth.

6. The partially-rotating or rocking collar A, provided with the set-screw k, and with the shifting weighted lever D, as and for the purposes set forth.

7. The combination, with the collar A, provided with the hooked spring-actuated arm E, of the lever G, pivoted to the arm E and attached to the weighted lever D by the rods f g, and bell-crank lever I, substantially as described.

8. The combination, with the collar A, provided with the hooked arm E, of the pivoted block H, attached to the weighted lever D by the rods h i, and bell-crank lever J, substantially as described.

9. The car-couplings herein shown and de-

scribed, consisting of the rotating, or partially rotating, collars A A, each provided with the hooked arms E E and catches F F upon opposite sides, and each provided with the weighted shifting-levers D D and with the set-screws k, the collars being adapted to be attached to the ordinary draw-heads, as described.

10. The collar A, adapted to be placed upon

the draw-heads, in combination with the pivoted hooked arm E, and the spring e, for holding the collar and arm evenly upon the draw-head, substantially as described.
